[57] CLAIM

The ornamental design for a combined telephone, telephone handset and telephone answering device, as shown and described.

DESCRIPTION

FIG. 1 is a front, top, right side perspective view of a combined telephone, telephone handset and telephone answering device showing our new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a bottom plan view thereof;

FIG. 8 is a perspective view, seen from the bottom, of a telephone handset used in the combined device of FIGS. 1-8;

FIG. 9 is a left side view thereof, the right side view being a mirror image;

FIG. 10 is a top plan view thereof;

FIG. 11 is a bottom plan view thereof;

FIG. 12 is a right end view thereof, as seen in FIG. 8; and,

FIG. 13 is a left end view thereof, as seen in FIG. 8.

The telephone handset has been shown separately in FIGS. 8-13 for convenience of illustration.
